UNITED STATES PATENT OFFICE.

ANDREW J. MILLER, OF NEAR ABINGDON, VIRGINIA.

CAR-COUPING.

SPECIFICATION forming part of Letters Patent No. 364,431, dated June 7, 1887.

Application filed February 7, 1887. Serial No. 226,828. (No model.)

To all whom it may concern:

Be it known that I, ANDREW J. MILLER, a citizen of the United States, residing near Abingdon, in the county of Washington and State of Virginia, have invented a new and useful Improvement in Car-Coupling Machines, which I call the "Jack Miller Car-Coupler," of which the following is a specification.

10 My invention relates to improvements in car-coupling machines, by which cars can be coupled and uncoupled without going between them, by the use of a crank operating under the car in conjunction with the machinery in the bumper; and the objects of my improvements are, first, to prevent accidents and to insure safety to the man operating, and secure more speed, accuracy, and certainty in coupling and uncoupling cars than in any 15 car-coupler now in use. I attain these objects by the mechanism illustrated in the accompanying drawings, in which—

Figure 1 is a vertical longitudinal section, showing the interior of the coupler, and the 25 arrangement of the parts when coupled. Fig. 2 is a bottom plan of the coupler, displaying it coupled also. Fig. 3 is a side elevation of the coupler as attached to a car and coupled. Fig. 4 is a vertical longitudinal view of two 30 couplers, each coupled. Figs. 5, 6, 7, 8, 9 are perspective views of the various component parts detached. Fig. 5 is a coupling-hook, the rear end (marked letter R) being longer than the forward end, and it is attached to 35 and secured in the bumper by a strong bolt passing through it at letter P. The position of the hook in the machine is shown on Fig. 3 by letter A. The hook turns easily on the bolt. Fig. 6 is a link guiding and coupling 40 and uncoupling device formed of two parts. The forward end of the upper part (marked letter r) is a forked notch used to move and guide the coupling-link in coupling the cars, and the rear end (marked letter D) is used to 45 raise, in conjunction with the crank operating on the lower part of the device, which is a lever, the clevis from the coupling-hook, so as to uncouple the car.

A is the draw-bar, mounted upon the car- 50 frame in the usual manner. It is provided with a through-recess, A', in which is arranged the coupling devices, and the front wall is provided with a link-receiving recess, A².

B is the coupling-hook, which is pivoted on 55 a bolt, B', passing through an eye in the hook and through the side walls of the draw-bar. The hook is formed with a front prong, b, which passes up through the coupling-link C, and secures it in the coupled position. It 60 has also a rear prong, b', longer than the front prong, over which the clevis D passes to hold the hook in coupled position.

D is a clevis or swinging link pivoted on 65 the bolt d.

E is the link guiding and uncoupling device. It is formed of two parts or curved levers, E' and E², united at E³. The part E' is made with a front fork to support and guide the link, and it curves upward and backward, terminating in an eye, C, through 70 which passes a bolt, e², pivoting the same in the draw-head.

E² is curved in the manner shown, having a projection or heel, e³, which is adapted to 75 carry the clevis D, and when operated lifts the clevis, allowing the coupling-hook to swing and uncouple. The lower part, e⁴, of this device is turned backwardly, forming a straight lever lying under the draw-bar.

Under the car-frame is pivoted a crank-shaft, F, in bearings f. This shaft is provided with handles projecting at either side of the car, by which it can be turned by the brakeman to either guide the link or uncouple the 85 cars. This shaft is provided with a downward loop, b², at its central part, and it engages the lever e⁴ of the link-guide and uncoupler in either of the two positions, as shown by dotted lines in Figs. 1, 3, 4.

From the description given above the operation of the device is obvious.

What I claim is—

1. The combination, with the curved hook B and link or clevis D, of the link guide and uncoupler pivoted in the draw-head and provided with the forward fork and rear projection or heel, e³, and the straight lever e⁴, substantially as described.

2. The combination, with the curved hook B and clevis D, of link guide and uncoupler pivoted in the draw-head and having the forward fork, the rear heel, and straight lever, and the crank-handles F, substantially as described.

ANDREW J. MILLER.
